(57) **CLAIM**

The ornamental design for a construction set for children, as shown and described.

DESCRIPTION

1. Construction set for children
2. Construction set for children
3. Construction set for children
4. Construction set for children
5. Construction set for children
- 1.1 Left
- 1.2 Front perspective
- 1.3 Right
- 1.4 Rear Perspective
- 1.5 Top
- 1.6 Cross-section of complete set (sectional view)
- 1.7 Exploded view of the set
- 2.1 Left
- 2.2 Front
- 2.3 Rear
- 2.4 Right
- 2.5 Top
- 2.6 Cross-section of complete set (sectional view)
- 2.7 Exploded view of the set
- 3.1 Left
- 3.2 Right
- 3.3 Perspective
- 3.4 Top
- 3.5 Cross-section of complete set (sectional view)
- 3.6 Exploded view of the set
- 4.1 Left
- 4.2 Right
- 4.3 Perspective
- 4.4 Cross-section of complete set (sectional view)
- 4.5 Exploded view of the set
- 5.1 Side
- 5.2 Cross-section of complete set (sectional view)
- 5.3 Exploded view of the unassembled set

1 Claim, 28 Drawing Sheets
